UNITED STATES PATENT OFFICE.

FRANK S. IRVINE, OF LONG ISLAND, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed September 11, 1920. Serial No. 409,694.

To all whom it may concern:

Be it known that I, FRANK S. IRVINE, a citizen of the United States, residing at Long Island, in the county of Suffolk, 5 State of New York, have invented certain new and useful Improvements in Telephone Systems, of which the following is a full, clear, concise, and exact description.

This invention relates to telephone systems and especially to systems employing machine switching equipment for extending talking connections.

In systems where finder switches of large capacity are used for extending the calling lines it has been the practice to divide a major group of lines into smaller groups and to provide a separate brush set in the finder switch to serve each of these smaller groups of lines. With such an arrangement the 20 set of brushes having access to the group containing the calling line may be selected and utilized to the exclusion of all remaining brush sets. The subdivision of a group of lines into smaller brush groups permits, 25 as may be seen, the use of a large capacity switch which requires a comparatively short maximum time interval in the selection of a calling line.

In order to decrease as much as possible 30 the operating period of the finder switches it is proposed to further divide the brush groups of lines into two subgroups. One of these subgroups of each brush group appears as first choice in half of the total 35 number of finders, assigned to handle the traffic in the major group of lines, and as second choice in the other half of the finder switches. Conversely, the other subgroup of each brush group appears as first choice 40 in the second half of the finders and as second choice in the first half of the switches. With the proper circuit provision a finder of the group serving as first choice the calling subgroup may always be used provided 45 such group of finders contains an idle one. Should all finders in a group be busy and a call be originated in a subgroup, normally served by such group of switches, then a finder in the other group, which 50 serves the calling line as second choice, may be started.

In case both groups of finder switches are simultaneously busy, a call initiated in either subgroup of lines would, of course,

fail to receive attention. It is desirable 55 that a record be kept of the frequency with which this condition occurs. This record gives the necessary information by which to judge the propriety of changing the number of finders to suit the traffic requirements. 60

It is, therefore, the object of this invention to provide, in a system of the character above set forth, means for taking a record each time a call is originated in any subgroup of lines when all finders of each of 65 the groups, which normally serve a different subgroup of lines, are simultaneously busy. Such other features as are contemplated in the present invention will become more apparent from the following detailed 70 description.

Referring to the drawing which constitutes a part of this disclosure, Figs. 1, 2 and 3, when taken in order from left to right, illustrate a portion of a telephone 75 system embodying one adaptation of the invention.

Fig. 1 shows two subscribers' telephone lines, one for each of the two subgroups of a group of lines served by the same set of 80 brushes in the finder switches. This figure also shows relays and circuits common to a subgroup of lines whereby originating calls are extended to the common starter circuit.

Fig. 2 shows a starter circuit common to 85 a plurality of brush groups of lines similar to the one shown in Fig. 1, the function of which is to initiate the operation of an idle finder switch in response to calls in said brush groups.

Fig. 3 illustrates diagrammatically two groups of finder switches for serving the two subgroups of lines of all brush groups.

In the system disclosed the division of the subscribers' lines into brush groups and subgroups, the method of connecting these lines to the terminal banks of the finder switches, the functions of the common starter circuit, the manner in which preference is given to calling line groups, the grouping 95 of the finder switches, the way in which these switches are allotted for use, and, in fact, the detailed operations involved in the extension of a calling line by a finder switch are substantially identical with 100 those more fully described in the patent to F. S. Irvine, No. 1,461,528, granted July 10, 1923. Reference to such application is 105

made for an explanation of such details of the system as are not considered necessary to include herein.

The line finder switches illustrated diagrammatically in Fig. 3 are of the well-known power driven panel type. These switches have a plurality of sets of brushes. Corresponding sets of brushes on all switches which serve a group of lines are arranged 10 to be tripped into operative engagement with the terminal bank by means of a common trip rod. The structural arrangement of the finder switches, whereby the proper set of brushes is selected and tripped by the 15 common trip rod, is illustrated and described in the patent to McQuarrie, No. 1,177,044, issued March 28, 1916.

Considering briefly the nature of the system in which this invention is incorporated, 20 it may be assumed that the subscribers' lines are arranged to appear in the line finder switches in major groups of 300 lines each, a major group of lines corresponding in number to the capacity of the finder switches. 25 Each major group of lines is divided into fifteen smaller groups, each of which is served by a different set of brushes in the finder switches. Further, a brush group is subdivided into two groups of ten lines each, 30 which, for convenience, may be termed the A and B subgroups. The A subgroup of lines of each brush group appear in the lower ten sets of terminals before the corresponding brushes of half of the total number 35 of finder switches serving a major group of lines. That is to say, the total number of finder switches serving a group of 300 lines are divided into two groups, the A and B groups. All A subgroups of lines appear 40 as the lower ten lines with respect to the corresponding brushes of all finders in the A group, while the B subgroups of lines appear as the lower ten lines before the brushes of all finder switches in the B group. In 45 addition the A subgroups of lines appear as the upper ten lines before the corresponding brushes in the B group of finders. And similarly the B subgroups of lines appear as the upper ten lines before the corresponding 50 brushes of the A finder switches.

Referring to the drawing, Fig. 1 shows one line, 100, in the A subgroup of a particular brush group and a corresponding line 101 in the B subgroup of the same brush group. 55 Above the horizontal broken line in Fig. 3 there are shown diagrammatically four line finder switches of the A group which normally serve as first choice all A subgroups of lines. Below the horizontal broken line 60 there are illustrated four line finder switches of the B group which likewise serve as first choice all B subgroups of lines. The line 100, for example, is seen to appear in terminals 300, 301, 302 and 303 in the lower ten 65 sets of terminals served by the brushes 304,

305, 306 and 307 of the first line finder switch of the A group. Similarly, it will be seen that this line appears in corresponding terminals in the lower ten sets of terminals served by brushes 319, 320, 321, etc., of all 70 succeeding finder switches in the A group. Furthermore, it will be noted that the line 100 is wired to terminals 343, 344, 345 and 346 in the upper ten sets of terminals before the brushes 330 of the first finder switch in the B group. It will be understood, of course, that the line 100 is also multiplied to corresponding sets of terminals in the upper ten sets of terminals served by brushes, such as 331, 332, 333, etc., of the remaining line 75 finder switches in the B group.

Line 101, which belongs to the B subgroup of the same brush group, appears as a first choice line in terminals 347, 348, 349 and 350 in the lower set of ten terminals served 80 by the brushes 330 of the first finder switch of the B group, and similarly before the brushes 331, 332, 333, etc., of the remaining B finders. Moreover, the line 101 appears in the terminals 308, 309, 310 and 311 in the upper ten sets of terminals of the first line 85 finder switch in the A group, and similarly in the upper ten sets of terminals of the remaining A finder switches. What has been said of lines 100 and 101 applies to all 90 other lines of this brush group and to the lines of both subgroups in the remaining brush groups not illustrated herein. To summarize briefly it may be said that all lines in the A subgroups are served as first 95 choice by the A group of finders, and as second choice by the B group of finders, and that all lines in the B subgroups are normally served as first choice by the B 100 group of finders and as second choice by the 105 finders of the A group.

The switch 200, shown in Fig. 2, is an ordinary step-by-step switch comprising the two brush arms 201 and 202. The purpose of this switch, as is fully explained in 110 my copending application above referred to, is to change the order in which brush groups of lines may acquire access to the common starter circuit in the event of simultaneous calls originating in different brush groups. 115 Inasmuch as the present invention is not particularly concerned with this feature, it has not been considered necessary to illustrate more than one brush group in order to show the method of changing the preferred 120 order.

To the right of Fig. 2 are shown two step-by-step switches 210 and 220 individual 125 respectively to the A and B groups of finder switches. The function of these switches is to change the order in which the finder switches are taken for use. With the preference switch 210 in its first position as shown in the drawing, first choice is given to the first finder switch in the A group. If 130

this finder switch be idle when a call is originated in an A subgroup, it is set in operation to find the calling line. If the first finder be busy, however, its relay 322 will be energized and the starter circuit is extended to the next finder in order shown in the A group, etc. At the initiation of each call the switch 210 advances one position whereby the first choice is given 10 to the next switch in order, second choice to the following switch and so on throughout the series. Likewise the same holds true with regard to the preference switch 220 and the B group of finder switches.

15 So long as the group of finders normally serving a particular subgroup of lines contains an idle switch, this switch will be taken for use to extend the calling line. When, however, all switches of the group, 20 normally serving as first choice a particular subgroup of lines, are busy and a call originates in such subgroup, then one of the switches of the other group of finders which serve this subgroup of lines as second choice 25 will be employed. For instance, assume all of the A finder switches were engaged at the time a call is originated in the A subgroup of any particular brush group. In a case of this kind the common starter circuit is 30 so designed that a finder switch in the B group will be started in operation, provided one is idle, to hunt for the calling line in the A subgroup of lines. If a call originates in either of the A or B subgroups at 35 the time that all finder switches of both the A and B groups are simultaneously busy, then, of course, the call must fail due to the fact that no switch is available for serving the same.

40 Considering now the detailed operation of the system it will be assumed that the subscriber to line 100 in the A subgroup wishes to obtain a telephone connection and that the first finder switch in the A group, normally serving this line as first choice, is idle. When the receiver is removed from the switchhook a circuit is established from battery through the winding of line relay 102, inner left-hand armature and contact of the 45 cut-off relay 103, conductor 113, over the loop at substation 100, conductor 114, contact and right-hand armature of relay 103 to ground. The line relay 102 becomes energized and completes a circuit for the 50 group relay 104, common to all lines in the A subgroup of this particular brush group, to ground at the left-hand armature and contact of relay 102. Relay 104 becomes energized and completes a circuit from ground 55 through its contact and armature, armature and contact of relay 105, left-hand armature and back contact of relay 106, left-hand winding of relay 107, conductor 123, outer left-hand armature and contact of relay 207, 60 outer left-hand armature and contact of re-

lay 208, contact and armature of stepping magnet 209, to battery and ground. Assuming the preference switch 200 to be standing in its first position, thereby assigning first preference to the brush group shown 70 in Fig. 1, relay 107 locks up over the following circuit: ground, through the right-hand normal contact of relay 106, right-hand winding and front contact and inner right-hand armature of relay 107, conductor 75 124, terminal 224, brush 201, left-hand armature and back contact of relay 203, back contact and inner right-hand armature of relay 206, winding of relay 207, to battery and ground. Relay 107, therefore, remains energized and relay 207 attracts its armatures. Relay 107 completes a circuit from ground 80 through its inner left-hand armature and contact, conductor 122, winding of trip magnet 313, Fig. 3, to battery and ground. The trip magnet 313 rotates the trip spindle 312 which is common to the corresponding set of brushes of all finders in both the A and B groups. The trip spindle in its rotated position prepares for the tripping of 85 the set of brushes on the particular finder switch that is started in operation to find the calling line.

Relay 207, which also energizes with relay 107, opens, at its outer left-hand armature 90 and contact, the circuit for the starter wire 123 to prevent the energization of another relay similar to relays 107 and 117 in any other brush group of lines until the finder switch serving this particular call is started 95 in operation. Relay 207 also closes a circuit from ground through its inner right-hand armature and contact, winding of the stepping magnet 209, to battery and ground. The stepping magnet 209, which belongs to 100 the switch 200, energizes preparatory to advance the brushes 201 and 202 of the preference switch to their next position terminals. Relay 207 further completes a circuit from ground through its outer right-hand 105 armature and contact, conductor 225, left-hand make-before-break contact of relay 215, brush 212, terminal 218, conductor 226, inner left-hand armature and back contact of relay 322, winding of relay 318, to battery 110 and ground. Relay 318 becomes energized and locks up in a circuit from ground through its winding and contact and inner left-hand armature to ground at the contact and armature of relay 314. Relay 318 closes 115 a circuit from ground through its outer left-hand armature and contact, contact and right-hand armature of relay 322, conductor 227, right-hand make-before-break contact and winding of relay 215, to battery and 120 ground. Relay 215 becomes energized and locks up in a circuit from battery through its winding, make-before-break contact and right-hand armature, contact and outer right-hand armature of relay 207 to ground. 125

130

Relay 215 completes a circuit from battery through the winding of the stepping magnet 213, brush 211, terminal 228, left-hand armature and make-before-break contact of relay 5 215, conductor 225, to ground at the contact and outer right-hand armature of relay 207. Stepping magnet 213, which belongs to the switch 210, becomes energized ready to advance the brushes 211 and 212 forward one 10 step.

Relay 318 also closes a circuit at its right-hand armature and contact for the updrive power magnet 316. Power magnet 316 causes the upward movement of the brush 15 shaft 315 whereby brushes 304, 305, 306 and 307 are tripped into operative engagement with the terminals of the bank. Shortly following the tripping operation the contact 342 is momentarily closed and a 20 circuit established from ground over said contact, conductor 229, back contact and left-hand armature of relay 205, conductor 125, contact and outer left-hand armature of relay 107, winding of relay 106, to battery 25 and ground. Relay 106 attracts its armatures and opens the holding circuit of relays 107 and 207. Relay 106 locks up in a circuit from battery through its winding and front contact and left-hand armature, contact and 30 armature of relay 105 to ground at the armature and contact of relay 104. Relay 106, at its right-hand armature and contact, closes a circuit for the right-hand winding of relay 105. This winding is non-inductively wound so that sufficient flux is not 35 produced to cause the operation of relay 105. The right-hand winding of relay 105, however, is capable of maintaining the armature of said relay attracted once it has been operated by the left-hand winding.

Relay 107, on deenergizing, opens the circuit of trip magnet 313. Relay 207, on releasing its armatures, again closes a conductor 123 to permit other calling lines to 45 obtain access to the common starter circuit. Relay 207, at its outer right-hand armature and contact, opens the circuits of relay 215 and stepping magnet 213. Magnet 213 de-energizes and advances brushes 211 and 212 50 forward one step. Relay 207, at its inner right-hand armature and contact, opens the circuit of stepping magnet 209 whereby the brushes 201 and 202 are moved forward to the next set of terminals.

55 The brush shaft 315 continues its upward movement until brushes 304, 305, 306 and 307 encounter terminals 300, 301, 302 and 303 of the calling subscriber's line 100. At this time a circuit is completed from ground 60 through the winding of relay 314, brush 307, test terminal 303, conductor 116, right-hand armature and contact of relay 102, contact and outer left-hand armature of relay 103, left-hand winding of relay 105, to battery and ground. Relay 105 becomes en-

ergized and opens the holding circuit of relay 106. Relay 106 is made slow to release and, therefore, does not retract its armatures immediately. During the time relay 106 is maintaining its armatures attracted, relay 70 105 is held operated over its right-hand winding.

Relay 314, which also becomes energized in series with relay 105, opens the circuit of relay 318, which in turn deenergizes and 75 opens the circuit of the updrive power magnet 316. The finder switch therefore comes to rest in engagement with the terminals of the calling subscriber's line. In the manner fully explained in the patent to F. 80 S. Irvine, No. 1,461,528, granted July 10, 1923, the cut-off relay 103 is energized over conductor 115, and line relay 102 releases its armatures to open the circuit of relay 104. Relay 104 becomes deenergized 85 and a short interval thereafter relay 106 also releases its armatures and opens the circuit of the right-hand winding of relay 105. Relay 105 thereupon deenergizes. All apparatus associated with the A subgroup of 90 this particular brush group is restored to normal to receive other calls.

When the brush shaft 315 of the finder switch moves away from its normal position, the off normal contact 326 is closed and 95 relay 322 becomes energized. This relay indicates the busy condition of the finder switch and serves to extend the starter wire by way of conductor 226, inner left-hand armature and front contact of relay 322, to 100 the inner left-hand armature of the relay 323 individual to the next finder switch in the series. After the call has been extended and the conversation completed, the finder switch is released by means of the down-drive power magnet 317, in the well-known manner.

Assume next that the subscriber to line 101 in the B subgroup wishes to extend a telephone connection. The removal of the receiver from the switchhook completes a circuit for the line relay 108 over the inner left-hand armature and contact of relay 109, conductor 119, through the loop of the substation, conductor 118, to ground at the right-hand 115 armature of relay 109. Relay 108, to ground at right-hand armature of relay 109. Relay 108, in a manner similar to that already described closes a circuit for relay 110. Relay 110 completes a circuit from ground through 120 its contact and armature, armature and contact of relay 111, left-hand armature and back contact of relay 112, left-hand winding of relay 117, conductor 123, left-hand armatures and contacts of relays 207 and 208, to battery 125 and ground through the contact and armature of stepping magnet 209. Relay 117 becomes energized and locks up over its right-hand winding through the first position terminal of brush 202 of the preference switch 130

200, left-hand armature and back contact of relay 204, back contact and inner right-hand armature of relay 205, winding of relay 208, to battery and ground. Relay 117 closes a 5 circuit from ground through its contact and inner left-hand armature, conductor 122, winding of trip magnet 313, to battery and ground. Relay 208 opens the starter circuit 123 to prevent other calls from reaching the 10 group circuit and also closes a circuit at its inner right-hand armature and contact for the energization of the stepping magnet 209. Relay 208, at its outer right-hand armature and contact, closes a circuit by way of conductor 230, left-hand make-before-break contact of relay 216, brush 222, terminal 223, conductor 231, to the armature of relay 334, and thence, as described, to the winding of a 15 relay corresponding to relay 318. The first 20 finder switch of the B group is thereby started in operation to position its brushes 330 on the terminals 347, 348, 349 and 350 of the subscriber's line 101 in the B subgroup. As already explained in the call above traced 25 in detail, relay 216 becomes energized, locks up and prepares a circuit for the stepping magnet 214 of the preference switch 220.

As soon as the brush set 330 has been tripped by the position trip rod 312, relay 112 30 becomes energized and locks up in the manner explained in connection with relay 106.

When the calling line has been found by the brushes 330, relay 111 becomes energized and opens the circuit of relay 112. Shortly 35 after this occurs the cut-off relay 109 is operated and relay 110 becomes deenergized. At the end of the necessary interval the slow to release relay 112 retracts its armatures and opens the circuit of the right-hand winding of relay 111.

When the first finder switch of the B group is taken for use, the relay 334 becomes energized in a circuit including the off normal contact 338 to indicate the busy condition of 40 this switch. The deenergization of relay 208, which occurs at the time relay 117 is released, opens the circuit of magnet 209 causing thereby the advance of the switch 200 to the next position. Relay 208, on deenergizing, also opens the circuit of the stepping magnet 214 and the switch 220 moves forward to change the order of preference in which the B finders are taken for use.

55 Assume now that a call is initiated on a line such as line 100 in the A subgroup at the time all of the A finder switches are busy. Since all of the A finders are already in use, relays 322, 323, 324, 325, etc., individual to these finders respectively are energized. Consequently, the following circuit is established for the energization of relay 203; ground, through the outer left-hand armatures and contacts of relays 325, 324, 323 and 322 in 60 series, conductor 232, left-hand winding of relay 203, to battery and ground. When, therefore, relay 107 becomes energized over its left-hand winding in response to the initiation of a call on line 100, the following circuit is established: ground, through the 70 right-hand normal contact of relay 106, right-hand winding and front contact and inner right-hand armature of relay 107, conductor 124, terminal 224, brush 201, left-hand armature and front contact of relay 203, 75 winding of relay 205, to battery and ground. Relay 205 becomes energized and closes a circuit from battery through the winding of relay 208, inner right-hand armature and front contact of relay 205, back contact and outer 80 right-hand armature of relay 204 to ground. Relay 208 attracts its armatures and causes the operation of one of the B finder switches as has already been explained. From this point on the operation of the selected B 85 finder to extend the calling line 100 in the A group progresses in the manner explained in detail in connection with the operation of one of these finders to extend a first choice line, such as line 101 in the B subgroup. Switch 220 is advanced one position as above described to change the order of preference in which the B finders are to be used.

Assume next that all of the finders of the B group are engaged at the time a call is initiated on a line, such as line 101, in the B subgroup normally served as first choice by the B finder switches. In view of the fact that all of the B finders are busy, relays 334, 335, 336 and 337 are energized and a series 100 circuit is established over their outer left-hand armatures and contacts, conductor 233, left-hand winding of relay 204, to battery and ground. Relay 204 is energized in this circuit. When relay 117 attracts its armatures in response to the initiation of a call on line 101 in the B subgroup, a circuit is established for holding this relay as follows: ground, through the right-hand normal contact of relay 112, right-hand winding and 110 front contact and inner right-hand armature of relay 117, conductor 126, brush 202, left-hand armature and front contact of relay 204, winding of relay 206, to battery and ground. Relay 206 completes a circuit from 115 battery through the winding of relay 207, inner right-hand armature and front contact of relay 206, to ground at the back contact and outer right-hand armature of relay 203. It is assumed, of course, that some finder in 120 the A group is idle and that consequently relay 203 is deenergized. Relay 207 operates as already explained to initiate the hunting movement of one of the finders of the A group to serve the calling line.

125 It has been seen how the A and B finders are normally taken for use to serve their first choice lines when any of the finders are idle at the time calls originate on such lines, and, furthermore, how either of these groups of 130

finders may be taken to serve their second choice lines whenever all finders in the normally assigned group are simultaneously busy. The last condition that may arise is 5 one in which a call is initiated in either the A or B subgroups at a time when all the finders of both the A and B groups are busy. This means a complete failure of the call to receive attention. In order that a record 10 may be taken of the frequency with which this condition arises, a register is installed which counts the number of times that calls fail to secure service on this account. Since all of the finders are busy the relays 322, 323, 15 324, etc. and relays 334, 335, 336, etc. are energized and both relays 203 and 204 are operated as above described. If then relay 107 becomes energized in response to the initiation of a call in the A subgroup, relay 205 20 is operated as explained. Relay 205 does not succeed in completing the circuit hereinbefore traced for relay 208 since this circuit is now opened at the back contact and outer right-hand armature of relay 204. Relay 205, 25 however, does close a circuit from battery through the winding of register 217, outer right-hand armature and contact of relay 205, front contact and outer right-hand armature of relay 204, to ground. The register 217 operates to register one count on the counting mechanism.

In a similar manner should a call originate in the B subgroup, relay 117 energizes and closes a circuit for relay 206. Similarly, 30 relay 206 fails to complete the energizing circuit of relay 207 in view of the fact that this circuit is already opened at the outer right-hand armature and back contact of relay 203. Relay 206, however, completes a 35 circuit for the register 217, traceable over the outer right-hand armature and contact of relay 206, to ground at the front contact and outer right-hand armature of relay 203. Register 207 accordingly takes another step 40 to record the initiation of another call which failed to secure service due to all finders being simultaneously busy.

What is claimed is:

1. In a telephone system, subscribers' lines 50 arranged in a plurality of groups, a plurality of groups of automatic switches, each group of switches arranged to normally serve a different one of said groups of lines, a register, and means responsive to the initiation of a call in any of said groups of lines when all the switches of all of said groups of switches are busy for operating said register.

2. In a telephone system, subscribers' lines 60 arranged in a plurality of groups, a plurality of groups of line finder switches, each group of switches arranged to normally serve a different one of said groups of lines, a register, means responsive to the initiation 65 of a call in any of said groups of lines when

all the finder switches of all of said groups of switches are busy for operating said register.

3. In a telephone system, subscribers' lines 70 arranged in a plurality of groups, a plurality of groups of automatic switches, each switch arranged to serve all of said groups of lines, each group of switches arranged to serve as first choice a different one of said groups of lines, a register, and means responsive to the initiation of a call in any of said groups of lines when all the switches of all of said groups of switches are busy for operating said register. 75

4. In a telephone system, subscribers' lines 80 arranged in a plurality of groups, a plurality of groups of automatic switches, each switch arranged to serve all of said groups of lines, each group of switches arranged to serve as first choice a different one of said groups of lines, means responsive to a call in any group of lines to operate an automatic switch in the group normally serving such group of lines as first choice, means for operating a switch in another group when all of the switches normally serving as first choice the group of lines containing the calling line are busy, a register, and means responsive to the initiation of a call in any of said groups of lines when all the switches of all of said groups of switches are busy for 85 operating said register. 90

5. In a telephone system, subscribers' lines 95 arranged in a plurality of groups, a plurality of groups of line finder switches, each finder arranged to serve all of said groups of lines, each group of finders arranged to serve as first choice a different one of said groups of lines, means responsive to the initiation of a call in any group for operating a finder switch of the group normally serving as first choice the group containing the calling line, means for operating a finder switch in another group when all of the finders of the group normally serving as first choice the group of lines containing the calling line are busy, a relay for each group 100 of finder switches, means for operating said relays when all of the finder switches of the corresponding groups are busy, a register, and means responsive to the initiation of a call in any group of lines when all of said relays are operated for actuating said register. 105

6. In a telephone system, subscribers' lines 110 arranged in two groups, a plurality of finder switches, each switch arranged to serve all of said lines, said switches being divided into two groups, each group serving as first choice a different one of said groups of lines, means responsive to the initiation of a call in either of said groups of lines for operating a finder switch normally serving as first choice that group of lines, means for operating a finder in the other group when all the find- 115 120 125 130

- ers normally serving as first choice the group of lines containing the calling line are busy, a register, and means responsive to the initiation of a call in either group of lines when 5 all of the finders of both groups of finders are busy for operating said register.
7. In a telephone system, telephone lines arranged in a plurality of groups, a plurality of groups of automatic switches, each 10 switch arranged to serve all of said groups of lines, each group of switches arranged to serve as first choice a different one of said groups of lines and a device for counting all calls initiated in any group of lines at a 15 time when all switches of all groups of switches are busy.
8. In a telephone system, subscribers' lines arranged in a plurality of groups, a plurality of groups of automatic switches, each 20 switch arranged to serve all of said groups of lines, each group of switches serving as first choice a different one of said groups of lines, a measuring device, and means responsive to the initiation of a call in any 25 group of lines and dependent on the simultaneous busy condition of all switches in one of said groups of switches for operating said measuring device.
9. In a telephone system, subscribers' lines arranged in a plurality of groups, a plurality of groups of automatic switches, each 30 group of switches arranged to serve as first choice a different one of said groups of lines, all switches arranged to serve all lines, means responsive to a call in any group of 35 lines to operate an automatic switch in the group normally serving such group of lines as first choice, means for operating a switch in another group when all of the switches normally serving the calling group are busy, a register, and means responsive to the initiation of a call in any group of lines and dependent on the simultaneous busy condition of all switches in one of said groups of switches for operating said register. 40
10. In a telephone system, subscribers' lines arranged in a plurality of groups, a plurality of groups of automatic switches, each switch having a plurality of brushes for making connection with said lines, each 45 group of switches arranged to serve normally a different one of said groups of lines, means for selecting the brushes of said switches, a register, and means responsive to the initiation of a call in any of said 50 groups of lines when all the switches of all groups of switches are busy for operating said register.
11. A telephone system comprising subscribers' lines arranged in groups, automatic finder switches of the panel type for extending said lines, a register, and means whereby a plurality of said switches jointly 55 operate said register.
- In witness whereof, I hereunto subscribe my name this 9th day of September, A. D. 1920.

FRANK S. IRVINE.
